UNITED STATES PATENT OFFICE.

GEORGE L. HESS, OF LA JUNTA, COLORADO.

FLUME.

1,008,466.

Specification of Letters Patent. Patented Nov. 14, 1911.

Application filed December 10, 1910. Serial No. 596,674.

To all whom it may concern:

Be it known that I, GEORGE L. HESS, a citizen of the United States, residing at La Junta, in the county of Otero, State of Colorado, have invented certain new and useful Improvements in Flumes; and I do hereby declare the following to be a full, clear, and exact description of the invention, such as will enable others skilled in the art to which it appertains to make and use the same.

This invention relates to flumes and particularly to that type employed in irrigation.

The object of the invention resides in the provision of a plural section flume of the character named which includes improved means for securing the sections together in a water-tight manner and which at the same time will offer the least resistance to the flow of water through the flume.

A further object of the invention resides in securing certain of the sections of the flume together in a water-tight manner so as to permit the sections so connected to move longitudinally with respect to each other without destroying such water-tight connection and thereby allow for the expansion and contraction of the sections of the flume and obviate the possibility of breakage or disarrangement of parts due to such expansion and contraction.

With these and other objects in view, the invention consists in the details of construction and in the arrangement and combination of parts to be hereinafter more fully described and particularly pointed out in the appended claims.

In describing the invention in detail, reference will be had to the accompanying drawings, wherein like characters of reference denote corresponding parts in the several views; and in which,

Figure 1 is a detail perspective view of a portion of a flume constructed in accordance with the invention; Fig. 2, a longitudinal section of Fig. 1; Fig. 3, a transverse section through one of the non-yielding connections between the flume sections; Fig. 4, a detail perspective view of the yielding connecting member employed between certain of the sections of the flume; and, Fig. 5, a detail perspective view of one of the wedging-shoes employed in the non-yielding connections between the flume sections.

Referring to the drawing, the portion of the flume illustrated in Fig. 1 is shown as comprising a plurality of sections 10, 11, 12, 13, 14 and 15. The section 10 is secured to the section 11 by means of a non-yielding connection. This connection is produced by forming one end of the section with a groove 16 and a resultant rib 17 extending throughout the entire transverse extent of the section 10. The end of the section 11 adjacent the section 10 is likewise formed with a groove 18 and a resultant rib 19 extending throughout the entire transverse extent of the section 11. The ribs 17 and 19 are depressed inwardly, as at 20 and 21 respectively, for a purpose that will presently appear. In connecting the sections 10 and 11 together, the rib 17 of the section 10 is seated in the groove 18 of the section 11 and the depth of the groove 18 is such that the inner faces of the sections 10 and 11 will be located in the same cylindrical plane. The sections 10 and 11 are secured together when in this relation by means of an outer clamping member A and an inner clamping member B. The outer clamping member A comprises a carrier rod 22 having its terminals threaded, as at 23. These threaded terminals 23 pass through the ends of the carrier beam 24 which extends across the sections of the flume. Nuts 25 mounted on the threaded terminals of the carrier rod serve when manipulated to draw the carrier rod firmly into the depression 21 of the rib 19, the seating of said carrier in this depression serving to secure the same against lateral displacement. The inner clamping member B comprises an arcuate bar 26 conforming to the configuration of the groove 16 so that when said member is seated in said groove the inner face thereof will register with and form a continuation of the inner faces of the inner sections 10 and 11. The ends of the inner clamping member B engage the carrier beam 24 at opposite ends of said beam respectively so that when the nuts 25 are manipulated to draw the carrier rod 22 into the depression 21, the inner clamping member B is forced into the groove 16 and an efficient clamping action between the inner and outer clamping members A and B had. In order to force the ends of the clamping member B outwardly during the clamping operation and thus equally dis-

tributing the force thereof, there is provided a pair of corresponding wedging shoes 27 mounted respectively on the terminals of the carrier rod 22 beneath the carrier beam 24. 6 Each of these wedging shoes is provided on its under face with an extension 28 having a cam face 29. This face is positioned for engagement with the inner edge of the adjacent end of the clamping member B so that 10 as the nuts 25 are manipulated during the clamping action a wedging effect will be produced to force the ends of the clamping member B outwardly and as a result distribute the force of such clamping action evenly. The sections 12 and 13 and likewise the sections 13 and 14 are connected to each other respectively in a manner similar to the sections 10 and 11 and a detailed description thereof will therefore be omitted. 15 20 The disarrangement of the various sections as the result of expansion and contraction is obviated by the following structure. The sections 11 and 12 are arranged with their adjacent ends overlapped, the end of 25 the section 11 being disposed against the inner face of the section 12. Surrounding the junction of the sections 11 and 12 is a connecting member C which is substantially V shaped and includes the angular arms 30 30 and 31, the free ends of which terminate in laterally extending portions 32 and 33 respectively which are disposed in turn respectively against the outer faces of the sections 12 and 11. The laterally extending portion 32 is then riveted to the section 11 to produce a water-tight joint, while the laterally extending portion 33 is similarly riveted to the outer face of the section 12. The arms 30 and 31 are shown soldered and 40 riveted together at their meeting point, although the connecting member C may be constructed with facility out of a single piece of material. The arms 30 and 31 possess sufficient resiliency to permit the 45 longitudinal movement of the sections 11 and 12 with respect to each other under the influence of expansion and contraction without in any manner disturbing the water-tight connection between said sections 50 formed by the member C. The sections 14 and 15 are connected to each other in a manner similar to the sections 11 and 12, and a detailed description thereof will therefore be omitted. By the use of the 55 connecting member C it will also be apparent that the flume can be bent laterally and also elevated or lowered at different points in its extent without in any manner disturbing the water-tight connections. 60 From the foregoing, it will be apparent that there has been constructed a flume which has a very small co-efficient of friction resulting in an increased carrying capacity of the flume, and further said flume may respond to expansion and con-

traction due to changes in temperature without in any manner injuring or disarranging the parts thereof.

What is claimed is:—

1. The combination of a pair of flume sections having their adjacent ends formed with interior grooves and resultant exterior ribs and disposed in overlapping relation with the rib of one section seated in the groove of the other section, the groove of the first named section being of less depth than the groove of the second named section whereby the inner faces of said sections are disposed in the same plane, and inner and outer clamping members, the inner clamping member being seated in the groove of the first named section and having its inner face positioned to form a continuation of the inner faces of said sections. 7

2. The combination of a pair of flume sections having their adjacent ends formed with interior grooves and resultant exterior ribs and disposed in overlapping relation with the rib of one section seated in the groove of the other section, said ribs being 80 provided with inwardly directed depressions, and the groove of the first named section being of less depth than the groove of the second named section whereby the faces of said sections are disposed in the same 85 plane, and inner and outer clamping members, the inner clamping member being seated in the groove of the first named section and having its inner face positioned to form a continuation of the inner faces of 90 said sections and the outer clamping member being seated in the depression of the second named section. 100

3. The combination of a pair of flume sections having overlapped ends, and an 105 angular member conforming to the configuration of the sections and having yielding arms, the free ends of which are 110 respectively secured to said sections so that said angular member covers the joint between the sections and the latter close communication between the interior of the sections and the space between the arms of the angular member. 115

4. The combination of a pair of flume sections having their adjacent end portions overlapped and provided with alternate depressions and eminences which interlock, an inner clamping bar disposed against the inner face of the inner overlapped portion 120 and conforming to the general shape thereof, and an outer clamping bar disposed against the outer face of the outer overlapped portion in clamping relation to the inner clamping bar. 125

5. The combination of a pair of flume sections having their adjacent end portions overlapped and provided with alternate depressions and eminences which interlock, an inner clamping bar disposed against the 130

inner face of the inner overlapped portion and conforming to the general shape thereof, an outer clamping bar disposed against the outer face of the outer overlapped portion in clamping relation to the inner clamping bar, and conforming in superficial shape to the part of the flume section with which it contacts.

6. The combination of a pair of flume sections having their adjacent ends overlapped and provided with corrugations which interlock, an inner clamping bar disposed in a groove of, and against the inner face of the inner corrugated overlapped end, an outer clamping bar disposed in a groove of,

and against the outer face of the outer corrugated overlapped end, in clamping relation to the inner clamping bar, and a spreading shoe mounted on each end of the outer clamping bar engaging respective ends of 20 the inner clamping bar and adapted to force the ends of the inner clamping bar outwardly during the clamping operation.

In testimony whereof, I affix my signature, in presence of two witnesses.

GEORGE L. HESS.
